DESIGN FOR A NECKTIE FASTENER OR SIMILAR ARTICLE

Charles Silverman, Providence, R. I.

Application April 11, 1936, Serial No. 62,068

Term of patent 7 years

To all whom it may concern:

Be it known that I, Charles Silverman, a citizen of the United States and resident of Providence, in the county of Providence and State of Rhode Island, have invented a new, original, and ornamental Design for a Necktie Fastener or Similar Article of which the following is a specification, reference being had to the accompanying drawing, forming part thereof.

In the drawing:

Fig. 1 is a front view of a necktie fastener showing my new design. The rear portion has been omitted for convenience of illustration, the initials shown in dotted lines being for purposes of illustration; it being understood that other letters of the alphabet may be used.

Fig. 2 is a rear view thereof, the dotted lines being omitted therefrom; and

Fig. 3 is a side view thereof.

I claim:

The ornamental design for a necktie fastener or similar article substantially as shown and described.

Signed at Providence, in the county of Providence and State of Rhode Island this 9th day of March A. D. 1936.

CHARLES SILVERMAN.
